US00D618540S

(12) **United States Design Patent**
Ruth

(10) **Patent No.:** **US D618,540 S**
(45) **Date of Patent:** **** Jun. 29, 2010**

(54) **DISPLAY PACKAGE UNIT WITH RETAINER
INSERT**

(75) Inventor: **James R. Ruth**, Miami, FL (US)

(73) Assignee: **TracFone Wireless, Inc.**, Miami, FL
(US)

(**) Term: **14 Years**

(21) Appl. No.: **29/316,817**

(22) Filed: **Nov. 4, 2009**

(51) **LOC (9) Cl.** **09-03**

(52) **U.S. Cl.** **D9/415**

(58) **Field of Classification Search** **D9/715, D9/721, 722, 414, 415, 416, 418, 420, 425, D9/426, 434, 435, 436; 206/320, 461-471, 206/775, 776, 781, 782, 562-564, 588-592**

See application file for complete search history.

(57) **CLAIM**

The ornamental design for the display package unit with retainer insert, as shown and described.

DESCRIPTION

FIG. 1 is a top front perspective view showing my new design for a display package unit with retainer insert in its assembled state;

FIG. 2 is a left side elevational view thereof;

FIG. 3 is a front view thereof;

FIG. 4 is a top view thereof;

FIG. 5 is a right side elevational view thereof;

FIG. 6 is a rear view thereof;

FIG. 7 is a bottom view thereof;

FIG. 8 is an opened and exploded perspective view thereof;

FIG. 9 is an inverted perspective view showing the opposing sides of the exploded design components in FIG. 8; and,

FIG. 10 is an opened perspective view showing the outer package and inner tray elements in their assembled state.

The broken lines showing the slider device contained within the display package unit are for illustrative purposes only; and form no part of the claimed design.
